LOOSE-LEAF BINDER

Alfred M. Martin, Park Ridge, Ill.

Application January 29, 1943, Serial No. 473,933

17 Claims. (Cl. 129—17)

1

This invention relates to loose leaf binders more particularly of the type shown in my Patent No. 1,269,479 of June 11, 1918, in which a pair of oppositely disposed angularly openable prong-holding parts are hinged together on a central longitudinally extending hinge so that one of the prong-holding parts may be moved a limited distance longitudinally of the other prong-holding part whereby record sheets impaled on the prongs in overlapping relationship to display a margin thereof may be shifted on one side of the binder to insert or remove a sheet. In my co-pending application Serial No. 338,063 which has matured as Patent No. 2,365,643, I disclosed and broadly claimed means for locking the prong-holding parts in partially open position while permitting shifting of the parts from out of normal oppositely disposed position to normal oppositely disposed position without releasing said locking means and for locking the parts against shifting upon shifting from the out of normal position to the normal position.

Among other objects, the present invention aims to present an improved and simplified binder of this type and in which unitary and compact mechanism is provided for releasably locking the parts in fully closed or in partially open position against further opening movement, while, in the partially open position, permitting relative longitudinal sliding of the parts in either direction without release of the mechanism, the mechanism at the same time normally inhibiting such relative sliding movement from the normal oppositely disposed position of the parts to the shifted position in the partially open position of the parts and positively prohibiting such shifting in the fully closed position of the parts.

For further simplification and saving of metal, the present binder is advantageously formed largely of wood or other fibrous or non-metallic material, the use of metal being in this instance limited to such parts as the prongs, locking mechanism and central hinge, and improved means being provided for assembling the metallic and non-metallic elements of the binder.

These and other objects and advantages will be apparent from the following description, taken together with the accompanying drawings forming a part of this specification and in which—

Figure 1 is a partial plan view of the binder looking at the inside thereof with the prong-holding parts in fully closed position and the covers open, the covers being broken away for simplification of the view and other parts being shown in section for clearness of description. This figure also indicates by a dotted line exten-

2

sion an alternative relatively longitudinally shifted position which is possible when the parts are partially or fully opened;

Figure 2 is a longitudinal sectional view taken on the line 2—2 of Fig. 1, and also of Fig. 3;

Figure 3 is a cross-sectional view taken on the line 3—3 of Fig. 1;

Figure 4 is a cross-section somewhat similar to Fig. 3 but showing the parts in partially open position;

Figure 5 is an end view of the binder looking at the lower end of Fig. 1 but showing the parts in a fully open position;

Figure 6 is a fragmentary plan view of the parts in the position as shown in Fig. 4;

Figure 7 is a still more fragmentary somewhat diagrammatical view of the parts shown in Fig. 6 with the locking mechanism in released position so that the parts may be fully opened;

Figure 8 is a plan view somewhat similar to Fig. 6 but showing the parts in relatively longitudinally shifted position while still locked in partially open position;

Figure 9 is a fragmentary cross-section taken on the broken line 9—9 of Fig. 8;

Figure 10 is a fragmentary longitudinal section taken on the line 10—10 of Fig. 8 and of parts shown therein;

Figure 11 is a view somewhat similar to Fig. 10 but showing the locking mechanism in released position whereby to permit full opening of the parts when the parts are in longitudinally shifted position;

Figure 12 is a reduced side elevational entire view of one of the prong-holding parts, in this instance the left-hand part looking at the latter from the hinge side of the part, a corresponding hinge of the adjacent part being indicated in separated relation in this figure;

Figure 13 is a perspective view, somewhat enlarged, of the locking mechanism looking at this from the upper right-hand corner of Fig. 1 but with the mechanism in unlocked position; and

Figure 14 is a fragmentary sectional view of one of the parts showing securement of a hinge leaf therein and being a partial section taken on the line 14—14 of Fig. 1.

Referring in detail to the drawings, the numerals 20 and 21 indicate the prong-holding parts generally in this instance, and which in accordance with the present invention, comprise a pair of wooden bases 22 and 23, each having an upstanding side 24 formed as here shown of wood or fibrous laminations for enhanced strength and non-warping characteristics. The sides 24 are shown secured to the bases 22 and 23 as by nails

25, preferably staggered for enhanced strength of attachment. Each prong-holding part 20 and 21 of the binder and the nails securing its parts together is desirably covered as in this instance by a fabric-like material 26, such as imitation leather, which is continued in two plies at the upper end of each side to cover the cover members 27 of the binder, the plies of the fabric as at 28 between the covers and the sides forming an articulate connection between the covers 27 and the sides 24, the core portions 27a of the covers being desirably of a heavier material such as press board to give the covers rigidity.

At the inner faces of the sides 24 which extend above the bases 22 and 23, each side carries a series of longitudinally spaced apart prongs 29 and 30 alternating on the parts respectively and arranged to more or less overlap as the binder is fully closed or opened. The prongs are carried in this instance by a metal plate 31, there being several prongs on a plate and these plates are shown secured as by rivets 32 to the sides of the prong-holding parts, the rivets 32 also advantageously reinforcing the attachment of the fabric covering 26 to the binder.

Along their lower adjacent corners, the bases 22 and 23 are shown kerfed as at 33 inwardly and longitudinally to receive hinge leaves 34 for the part 22 and hinge leaves 35 for the part 23. To effect a tight fit of the hinge leaves in the wooden parts, the kerfs 33 advantageously first receive strips of fibrous material 36, in overlying relationship in each kerf, and a hinge leaf 34 or 35, as the case may be, is forced into the kerf between the fiber strips 36, which thus serve somewhat as shims to center the leaf and prevent chattering of the leaf in the kerf. To further secure the leaf in the kerf, skewers 37 are shown driven into the wood of the binder part, as best shown in Fig. 14, and through piercings 38 pre-formed in the hinge leaves, the heads 39 of the skewers being somewhat countersunk in the wood and being smoothly concealed by the overlying fabric covering 26.

The leaves 34 carry the usual hinge sleeves 40 and 41 and the hinge leaves 35 carries the usual hinge sleeve 42. In this instance, as best shown in Fig. 12, there are three of these pairs of hinge leaves spaced longitudinally of the binder, a pair consisting of a hinge leaf 34 and a hinge leaf 35, with the hinge sleeve 42 on the hinge leaf 35 interposed between the hinge sleeves 40 and 41 of the hinge leaf 34. Pintle means are provided such as the hinge rod 43, which is not shown in Fig. 12 but is seen in other figures of the drawings (see Fig. 2) and is of substantially the length of the binder, passing through all the pairs of aligned hinge sleeves. To secure the hinge rod 43 the tips of the end-most hinge sleeves may be slightly crimped over the rod as at 45, Figs. 2, and 5.

The hinge sleeve 42 is enough shorter than the distance between the hinge sleeves 40 and 41, in each case, so that the prong-holding parts of the binder may shift relatively longitudinally, as indicated in dotted lines at 44, Fig. 1, a distance equal to the exposed margins of the record sheets which are to be impaled upon the prongs 29 and 30, thus to accommodate the removal or insertion of a sheet in the usual manner well known with respect to shift binders of this type.

Further in accordance with the present invention, the locking means, as here shown, for the prong-holding parts, will now be described in detail. On the prong-holding part 20, in this in-

stance, centrally longitudinally of this part, is carried a locating plate 46 fastened to the wood of the prong-holding part as by nails 47. Near its edge margining the mating edges of the two prong-holding parts 20 and 21, the locating plate 46 is apertured at each end as at 48 (Fig. 9) to threadedly receive screws 49 which further secure the locating plate to the prong-holding part 20 and pass down through the body of the latter, advantageously to have their tips received in pre-formed piercings as at 50, in the central hinge leaf 34 of the binder, thus serving further to secure the parts.

It is arranged that when the screws 49 contact 15 the hinge leaf 34 the heads of the screws 49 are spaced above the locating plate 46, providing room therebeneath for a floating support 51 for a bridge member 52 of the locking mechanism. The floating support 51 is apertured at each end 20 as at 53 to freely pass the unthreaded portion of the shanks of the screws 49 therethrough, these apertures being slightly oversize for the diameter of the screw shank and thus permitting ready rocking movement of the floating support 51 limited only by the heads of the screws 49.

The bridge member 52 is secured transversely to its floating support 51 as by spot-welding at 54 and is continued rearwardly therefrom to overlie a well-hole 55 in the prong-holding part 20 into which is first dropped a compression coil spring 56, the upper end of which bears against the under face of the bridge member 52 and urges the rear end of the bridge outwardly. To retain these parts in engagement the bridge 30 member is advantageously bent downwardly at its rear end as at 57, and, in the depressed position of this bent portion, the latter is received in a recess 58 provided jointly in the locating plate 46 and the wood of the prong-holding part 20 as 40 best seen in Fig. 3. At its distal end the bridge member 52 has a down-turned lip 59 and the spring 56 thus urges the lip 59 toward the adjoining prong-holding part 21 (or perpendicularly to the hinge 43), the bridge member being 45 advantageously angled slightly as at 60 in furtherance of this latter result.

Upon the adjoining prong-holding part 21, opposite the locating plate 46, is carried another locating plate 61 for the other elements of the locking mechanism. Since these include elements 50 which are not only longitudinally slideable with respect to the bridge 52 but slideable with respect to each other, the locating plate 61 carries at each end straps 62 and 63, under which and upon the locating plate 61 slides the lock bar 64. At each side of the lock bar the straps 62 and 63 are depressed as at 62a and 63a respectively to have face to face contact with the locating plate 61 and these elements are drilled as at 65 to pass therethrough screws 66 which secure the locating plate 61 with its superposed straps 62 and 63 firmly to the prong-holding part 21. To further secure the straps and locating plate together, spot-weldings 67 may be made adjacent the drill 65 holes 65.

The lock bar 64 is urged in one direction by the helical compression spring 68 which at one end is anchored to a screw 69 threaded into the prong-holding part 21 and at its other end abuts 70 the lock bar, which has a tip 70 to receive the coils of the spring and maintain this engagement. In compression of the spring, the coils hug the screw head 69 and are kept in line thereby.

Between the straps 62 and 63 the locating plate 75 61 carries a latch member or device comprising

jointly a pair of latch member portions 71 and 72. The latch member 71 is fixed on the locating plate 61 as by being welded thereto as at 73 abutting the strap 63, while the latch member 72 is movable between the latch member 71 and the strap 62, the latch member 72 being carried on the under face of the lock bar 64 and spot-welded thereto as at 74. Thus the fixed latch member 71 forms a stop at one end for the movable latch member 72, and the strap 62 forms a stop at the other end of its movement for the movable latch member. The lock bar 64 is offset as at 75 to provide space between it and the locating plate 61 to receive the movable latch member 72. The strap 63 is shown elevated above the strap 62 where the lock bar 64 passes thereunder and here the lock bar 64 carries a cam or elevator block 76, movable with the lock bar, the purpose of which will be later explained.

In the normal position of the lock bar 64 to which it is urged by the spring 68, the latch member portions 71 and 72 are in abutment. When the prong-holding parts 20 and 21 are in fully closed position as in Figs. 1 and 3, at which time they are also in normal oppositely disposed relationship as shown in full lines in Fig. 1, the bridge member 52 spans the latch member 72 and the lip 59 catches on the rear edge 77 of the latch member 72. Thus the binder is locked in fully closed position. At the same time, to prevent shifting of the prong-holding parts longitudinally in this fully closed position of the binder, the lip 59 longitudinally abuts the fixed latch member 71.

When it is desired to open the prong-holding parts from their fully closed position, the lock bar 64 is actuated by the clerk or other user. For this purpose, the lock bar 64 has attached thereto an actuating shank 78 which extends to the proximal end of the binder and terminates in a thumb-piece 79. Adjacent this end, the shank 78 passes slidably under a guide 80 secured as by screw 81 to the prong-holding part 21. When the thumb-piece 79 is pressed, against the force of the spring 68, the lock bar shank 78 and with it the locking bar 64 moves in the direction of the arrow 82 (Figs. 7 and 13), separating the locking edge 77 of the latch member 72 longitudinally from the lip 59 of the bridge 52. That is to say, since the latch member 72 moves longitudinally when the thumb-piece 79 is pressed, it is moved out of transverse or locking alignment with the bridge 52.

When the bridge 52 has compressed the spring 56 in its well-hole 55, as shown in Fig. 3, and the floating support 51 of the bridge is tilted to the limit of its movement away from the prong-holding part 21 as determined by the screws 49, the spring 56 cannot be accidentally further compressed to unintentionally release the locking mechanism. To release the latter, the thumb-piece 79 must be pressed, and when this is done as already pointed out, the prong-holding parts 20 and 21 are permitted to open. If it is not desired to open these parts fully, the thumb-piece, after being pressed, is immediately released, and, as the binder opens, the lip 59 of the bridge will catch on the upstanding flange 83 of the latch member portion 72, the latch member having now returned from the position shown in Fig. 7, under the influence of the spring 68, to the position shown in Fig. 6, that is, into transverse alignment with the bridge 52. The flange 83, it will be seen, is at the end of the latch member 72 adjacent the other part of the binder 20 and

the parts 20 and 21 are thus held in partially open position, as shown in Figs. 4 and 6.

At this time, the parts 20 and 21 are positively but releasably held against relative longitudinal movement by longitudinal abutment of the bridge lip 59 with another upstanding flange or locking surface 84 carried by the fixed latch member 71. To this end, the flanges 83 and 84 are relatively staggered transversely of the binder, the flange 83 of the movable latch member portion 72 being off-set, to the extent of substantially the thickness of the lip 59, further toward the prong-carrying part 20. So that the binder may be readily closed, if desired, from this position shown in Fig. 6 back to the position shown in Fig. 3, without actuation of the thumb-piece 79, the parts are arranged so that the lip 59 will not catch on the lock bar 64, as best seen in Fig. 4. Thus when the parts are pressed together from this position, the lip rides readily over the lock bar 64. The bridge 52, being now depressed at its lip end by the spring 56, will re-engage the locking edge 77 of the movable latch member 72.

If, however, it be desired to open the binder further from the partially open position shown in Fig. 4, to the fully open position shown in Fig. 5, the thumb-piece 79 is again pressed, and the lock bar is again moved longitudinally against the action of the spring 68 and in the same direction shown by the arrows 82 (Fig. 7 and Fig. 13) this time to move the flange 83 longitudinally of the lip 59 and thus disengage these parts so that the lip 59 may pass through a slot 85 now formed between the latch flanges 83 and 84, thus releasing the parts 20 and 21 for further opening movement.

Following the present invention, it is not necessary to open the binder to the fully open position shown in Fig. 5 in order to shift the prong-carrying parts relatively and whereby one of these parts, such as the part 20, may occupy the shifted position shown in dotted lines at 44 of Fig. 1. A marked advantage of the present invention is that while the prong-carrying parts 20 and 21 are normally held against accidental shifting when in partially open position as well as when in fully closed position, they may be so shifted when partially open without actuating the release mechanism, and this is readily accomplished by grasping the prongs 29 and 30 and manually moving the prong-carrying parts slightly together toward the fully closed position just sufficient so that the lip 59 of the bridge 52 is removed from longitudinal abutment with the flange 84 of the fixed latch member 71. Thereupon, as shown in Fig. 8, the prong-carrying part 20 and with it the bridge 52 may be shifted in the direction shown by the arrow 86 and as indicated by the dotted lines 44, Fig. 1.

During this movement, the prong-carrying parts 20 and 21 are still prevented from opening to the position shown in Fig. 5 by the fact that the flange 84 of the fixed latch member 71 acts as a stop against transverse movement of the bridge 52, the lip 59 now abutting the flange 84 transversely, as shown in Figs. 8, 9 and 10, and abutting the strap 63 longitudinally as shown in Figs. 8 and 10, this being also the limit of movement in this instance of the hinge sleeves 42 between the hinge sleeves 40 and 41.

When, now, it is desired to open the binder parts to the fully open position shown in Fig. 5, to remove record sheets from the prongs or to insert record sheets thereon, and with say the prong-carrying parts in the shifted position last

described, the thumb-piece 79 is once more pressed to actuate the release mechanism and thereupon the locking bar 64 again moves in the direction of the arrow 82 against the force of the spring 68. At this juncture the cam block 76, already previously mentioned as being carried by the lock bar 64, comes into play to separate the lip 59 transversely from the latch flange 84. For this purpose, the cam block 76 at its forward end has a cam incline 87, normally underneath the strap 63 (see Figs. 6 and 10) which, as will be seen from the drawings (see Figs. 11 and 13), causes upward movement of the lip 59 from out of abutment with the latch flange 84. Since the cam block 76 is of a thickness substantially equivalent to the height of the latch flange 84 and since the lip 59 is caused by the cam incline 87 to ride up onto the main body of the cam or elevator block 76 and be thus lifted free of the flange 84, the prong-holding parts may be then opened to the position shown in Fig. 5.

To close the binder, the prong-holding parts 20 and 21 are preferably first shifted back from the out of normal oppositely disposed position to normal oppositely disposed position. This may be done whether the parts are in fully open position or in partially open position. If the parts be in partially open position they will be locked against further opening movement while still being readily slidable longitudinally from the shifted, or out of normal oppositely disposed position to the normally oppositely disposed or unshifted position, that is, from the position shown in Fig. 8 to the position shown in Fig. 6, the arrangement of relative off-set of the flanges 83 and 84 not inhibiting sliding movement in this return direction. When the parts are again in normally oppositely disposed position as shown in Fig. 6, they are still locked against movement to a fully open position and the binder may be fully closed by again moving the prong-holding parts 20 and 21 angularly together to register the locking engagement of the lip 59 with the locking edge 77 of the movable latch member 72.

It is desirable that the prong-holding parts 20 and 21 should be incapable of being locked in the fully closed position when the prong-holding parts 20 and 21 are in the shifted position shown in dotted lines in Fig. 1, and, to this end, the fixed latch member 71 is advantageously longer transversely of the binder than the movable latch member 72. Conversely, to facilitate catching of the lip 59 on the edge 77 of the movable latch member 72 in the unshifted position of the parts and when it is desired to fully close the parts and to so lock the parts, the locating plate 61 is desirably cut away beneath the path of movement of the edge 77 as at 88.

The bridge member 52 constitutes a single locking member on one of the prong-holding parts, the part 20, engageable with a member having portions 71 and 72 on the other prong-holding part, or part 21, to perform all of the locking functions of the device.

To limit movement of the lock bar 64, within the limits already described, and for other advantageous purposes, the shank 78 of the lock bar is shown welded thereto as at 89 so that the underhanging end 90 of the shank and the offset 75 of the lock bar 64 will abut the other latch members when the lock bar 64 is moved sufficiently to cause the gap or slot 85 between the latch flanges 83 and 84 to be just enough longer than the width of the lip 59 to permit the latter to pass freely therethrough, as best seen in Fig. 7, and

also in the shifted position of the parts, to cause the cam block 76 to move under the lip 59 a sufficient distance to raise the lip above the flange 84 (Fig. 11).

It is to be understood that the invention is not intended to be limited to details of construction here shown for illustrative purposes. Other modifications will suggest themselves to those skilled in the art and having the benefit of the present disclosure. Furthermore, it is not intended that it be understood that all features of the present disclosure must be used conjointly, since it will be apparent to workers in the art that various combinations or sub-combinations may at times be advantageously employed.

The invention having been described, what is here claimed is:

1. In a loose leaf binder having a pair of oppositely disposed relatively opening prong-holding parts, the combination with means for guiding one of the parts for movement longitudinally with respect to the other, of locking mechanism for the parts comprising a latch member on one of the parts having a longitudinally slidable portion, a bridge member on the other prong-holding part having a lip engageable with said longitudinally movable latch portion in two places, in one place to maintain the prong-holding parts fully closed and in another place to maintain the prong-holding parts partially open, said lip having longitudinal engagement with the latch portion which is not longitudinally movable also in two places to inhibit longitudinal movement of the longitudinally movable prong-holding part with respect to the other, a cam movable with the longitudinally movable latch portion, said cam serving to disengage the lip and latch portion which is not longitudinally movable, a spring normally urging said longitudinally movable latch portion into position for engagement with said lip, another spring urging said bridge member toward said latch member, and means for moving the longitudinally movable latch portion and cam.

2. In a loose leaf binder having a pair of oppositely disposed relatively opening prong-holding parts, the combination with means for guiding one of the parts for movement longitudinally with respect to the other, of locking mechanism for the parts comprising a latch member on one of the parts having a longitudinally slidable portion, a bridge member on the other prong-holding part having a lip engageable with said longitudinally movable latch portion in two places, in one place to maintain the prong-holding parts fully closed and in another place to maintain the prong-holding parts partially open, said lip having longitudinal engagement with the latch portion which is not longitudinally movable also in two places to inhibit longitudinal movement of the longitudinally movable prong-holding part with respect to the other, a spring normally urging said longitudinally movable latch portion into position for engagement with said lip, another spring urging said bridge member toward said latch member, said bridge being intermediately pivoted on a floating connection and the last mentioned spring being a compression spring urging the end of the bridge member opposite said lip outwardly to tilt the bridge member inwardly at its lip end.

3. In a loose leaf binder having a pair of oppositely disposed relatively opening prong-holding parts hinged together on a central longitudinally extending hinge, the combination of locking mechanism for the parts comprising a latch mem-

ber on one of the parts longitudinally movable to locking and unlocking positions, a bridge member on the other prong-holding part movable in a direction at right angles to said hinge and having a lip engageable with said longitudinally movable latch to maintain the prong-holding parts against opening movement, and a spring normally urging said longitudinally movable latch into position for engagement with said lip, another spring urging said bridge member toward said latch, said latch and lip when the latch is moved longitudinally to unlocking position being disengaged to permit opening movement of the parts.

4. In a loose leaf binder having a pair of oppositely disposed relatively opening prong-holding parts, the combination of locking mechanism for the parts comprising a latch member on one of the parts longitudinally movable to locking and unlocking positions, a bridge member on the other prong-holding part having a lip engageable with said longitudinally movable latch in two places, in one place to maintain the prong-holding parts fully closed and in another place to maintain the prong-holding parts partially open, said latch and lip when the latch is moved longitudinally to unlocking position being disengaged to permit opening movement of the parts.

5. In a loose leaf binder having a pair of oppositely disposed relatively opening prong-holding parts hinged together on a central longitudinally extending hinge, the combination of locking mechanism for the parts comprising a latch member on one of the parts having a longitudinally movable portion and a fixed portion, a bridge member on the other prong-holding part movable in a direction at right angles to said hinge and having a lip engageable with said latch member to maintain the prong-holding parts partially open, a cam carried by the longitudinally movable latch portion for moving the bridge member to disengage the lip and latch to permit further opening movement of the parts, means for actuating the cam, and springs associated with each of the bridge member and longitudinally movable latch portion for normally urging said longitudinally movable latch portion and lip into engagement.

6. In a loose leaf binder having a pair of oppositely disposed relatively opening prong-holding parts, the combination with means for guiding one of the parts for movement longitudinally with respect to the other, of partially open selectively releasable locking mechanism for the parts comprising means on one of the parts engageable with means on the other part, the said means being relatively slidable while inhibiting further opening movement of the parts when the parts are moved relatively longitudinally in either direction, and interengaging elements between the said means inhibiting said longitudinal movement of the parts when the parts are in normal oppositely disposed position, said interengaging elements comprising a bridge member having a lip on one of said means and transversely offset portions on the other said means, said lip and one of said transversely offset portions having longitudinal abutment in the unshifted position of said prong-holding parts, said bridge member carrying said lip being pivoted intermediately and being spring pressed on said pivot toward said transversely offset portions.

7. In a loose leaf binder having a pair of oppositely disposed relatively opening prong-holding parts, the combination with means for guiding

one of the parts for movement longitudinally with respect to the other, of partially open selectively releasable locking mechanism for the parts comprising means on one of the parts engageable with means on the other part, the said means being relatively slidable while inhibiting further opening movement of the parts when sliding from other than normal oppositely disposed position to normal oppositely disposed position, and interengaging elements between the said means inhibiting said longitudinal movement of the parts when the parts are in normal oppositely disposed position, said interengaging elements comprising a bridge member having a lip on one of said means and transversely offset portions on the other said means, said lip and one of said transversely offset portions having longitudinal abutment in the unshifted position of said prong-holding parts, said bridge member carrying said lip being spring pressed toward said transversely offset portions.

8. In a loose leaf binder having a pair of oppositely disposed relatively opening prong-holding parts, the combination with means for guiding one of the parts for movement longitudinally with respect to the other, of partially open selectively releasable locking mechanism for the parts comprising means on one of the parts engageable with means on the other part, the said means being relatively slidable while inhibiting further opening movement of the parts when sliding from other than normal oppositely disposed position to normal oppositely disposed position, and interengaging elements between the said means inhibiting said longitudinal movement of the parts when the parts are in normal oppositely disposed position, said interengaging elements comprising a bridge member having a lip on one of said means and transversely offset portions on the other said means, said lip and one of said transversely offset portions having longitudinal abutment in the unshifted position of said prong-holding parts.

9. In a loose leaf binder having a pair of oppositely disposed relatively opening prong-holding parts having a fully open and a fully closed position and a partially open position, the combination with means for guiding one of the parts for limited sliding movement longitudinally with respect to the other, of selectively releasable locking mechanism for the parts comprising a single member on one of the parts engageable with another member on the other part, the said members being relatively slidable while inhibiting opening movement of the parts from partially open to fully open position when sliding from other than normal oppositely disposed position to normal oppositely disposed position, interengaging means between the members inhibiting said longitudinal movement of the parts when the parts are in normal oppositely disposed position in both the fully closed position and the partially open position of the parts, said locking mechanism being actuatable initially to permit opening movement of the prong-holding parts from fully closed position to partially open position and being further actuatable to permit further opening of the prong-holding parts from partially open position to fully open position, said locking mechanism having a unitary actuating bar common to both actuations, and connected with a member on the part opposite the part which has the said single member.

10. In a loose leaf binder having a pair of oppositely disposed angularly relatively movable

prong-holding parts having a fully closed position, a partially open position, and a fully open position, a hinge between the parts arranged for guiding one of the parts for limited shifting movement longitudinally with respect to the other part to and from the normal oppositely disposed position of the parts, and means for holding said parts releasably from movement from partially open position to fully open position during said longitudinal movements, that improvement therein wherein said means includes catch means inhibiting longitudinal movement of the prong-holding parts from normal oppositely disposed position to out of normal oppositely disposed position when the parts are in partially open position, said catch means being arranged to be released by manual movement of the parts on said hinge toward the fully closed position of the parts during movement from the normal oppositely disposed position to the out of normal oppositely disposed position while simultaneously prohibiting movement from the partially open position to the fully open position during said longitudinal shifting movement in either direction.

11. In a loose leaf binder having a pair of oppositely disposed relatively opening prong-holding parts having a fully closed position, a partially open position, and a fully open position, the combination with means for guiding one of the parts for shifting movement longitudinally with respect to the other, of locking mechanism for the parts comprising a latch member on one of the parts having a longitudinally slidable portion, a bridge member on the other prong-holding part having a lip engageable with said longitudinally movable latch portion in two places, in one place to maintain the prong-holding parts fully closed and in another place to maintain the prong-holding parts partially open, said lip having longitudinal engagement with the latch portion which is not longitudinally movable also in two places to inhibit longitudinal movement of the longitudinally movable prong-holding part with respect to the other in the fully closed and partially open positions, respectively, means for moving longitudinally the said longitudinally movable latch portion to effect opening movement of the prong-holding parts when the parts are in unshifted position, means for separating said lip from said latch portion which is not longitudinally movable to effect opening movement of the prong-holding parts when the parts are in longitudinally shifted position, and a common actuating member for both last mentioned means, said lip and latch member normally releasably inhibiting opening movement of the parts from partially open position to fully open position during shifting movement of the parts in either direction.

12. In a loose leaf binder having a pair of oppositely disposed relatively opening prong-holding parts, the combination with means for guiding one of the parts for movement longitudinally with respect to the other, of locking mechanism for the parts comprising a latch member on one of the parts having a longitudinally slidable portion, a bridge member on the other prong-holding part having a lip engageable with said longitudinally movable latch portion in two places, in one place to maintain the prong-holding parts fully closed and in another place to maintain the prong-holding parts partially open, said lip having longitudinal engagement with the latch portion which is not longitudinally movable also in two places to inhibit longitudinal movement

of the longitudinally movable prong-holding part with respect to the other, means for moving longitudinally the said longitudinally movable latch portion to effect opening movements of the prong-holding parts when the parts are in unshifted position, and means for separating said lip from said latch portion which is not longitudinally movable to effect opening movement of the prong-holding parts when the parts are in longitudinally shifted position.

13. In a loose leaf binder having a pair of oppositely disposed angularly opening prong-holding parts and having a fully closed position, a partially open position and a fully open position, 15 a hinge arranged for guiding one of the parts for limited longitudinal shifting movement relatively to the other to and from the normal oppositely disposed position of the parts whereby the parts have both a normal oppositely disposed and an out of normal oppositely disposed longitudinal position, means for holding said parts releasably against movement from partially open position to fully open position while the parts are in either longitudinal position for effecting movement of the parts from out of normal oppositely disposed position of the parts to normal oppositely disposed position or from normal oppositely disposed position to the out of normal oppositely disposed position without releasing said 20 means whereby throughout said last mentioned movements the said parts are held from moving from partially open position to fully open position, said means including positive releasable interengaging stop means on the parts brought into engagement by movement of the parts from out of normal oppositely disposed position to normal oppositely disposed position for releasably prohibiting longitudinal movement of the parts when the parts are in normal oppositely disposed position but with the parts partially open, said 25 stop means being releasable without releasing the means for holding the parts from opening from partially open position to fully open position.
14. In a loose leaf binder comprising a pair of angularly opening oppositely disposed prong-holding parts having a fully closed position, a partially open position and a fully open position, and having a medial hinge therebetween whereby 30 one of the parts may be shifted a limited distance longitudinally of the other from the normal oppositely disposed position of the parts to an out of normal oppositely disposed position, that improvement therein wherein there is a member on one of the parts engageable with a member on the other part, the said members being relatively longitudinally slidable while releasably preventing opening movement of the parts from a partially open position to a fully open position, and means carried jointly by said members brought into longitudinal abutment by movement of said parts from fully closed position to partially open position for releasably preventing shifting of the parts from normal oppositely disposed position to out of normal oppositely disposed position when the parts are locked from opening from partially open position to fully open position, said means being releasable by slight movement of the parts from partially open position toward the fully closed position to place said means out of longitudinal abutment and to permit shifting of the binder to said out of normal oppositely disposed position while still preventing opening of the parts
- 35 40 45 50 55 60 65 70 75

from partially open position to fully open position.

15. In a loose leaf binder comprising a pair of angularly opening oppositely disposed prong-holding parts having a fully closed position, a partially open position and a fully open position and having a medial hinge therebetween whereby one of the parts may be shifted a limited distance longitudinally of the other from the normal oppositely disposed position to an out of normal oppositely disposed position, that improvement therein wherein there is a member on one of the parts and a two portion latch device on the other part for releasably preventing opening movement of the parts from a fully closed position to a partially open position and from a partially open position to a fully open position by engagement of said member with said latch device in two places respectively spaced apart transversely of the parts, and means in longitudinal abutment on said member and latch device jointly for releasably preventing shifting of the parts from said normal oppositely disposed position to said out of normal oppositely disposed position in both the fully closed position of the parts and the partially open position of the parts.

16. In a loose leaf binder comprising a pair of angularly opening oppositely disposed prong-holding parts having a fully closed position, a partially open position and a fully open position and having a medial hinge therebetween whereby one of the parts may be shifted a limited distance longitudinally of the other from the normal oppositely disposed position to an out of normal oppositely disposed position, that improvement therein wherein there is a lip carrying member on one of the parts and a two portion latch device on the other part for releasably preventing opening movement of the parts from a fully closed position to a partially open position and from a partially open position to a fully open position by engagement of said lip with said latch device in two places respectively spaced apart transversely of the parts, and means in longitudinal abutment on said lip and latch device jointly for releasably preventing shifting of the

parts from said normal oppositely disposed position to out of normal oppositely disposed position in the partially open position of the parts.

17. In a loose leaf binder having a pair of oppositely disposed relatively opening prong-holding parts hinged together on a central longitudinally extending hinge, the combination of locking mechanism for the parts comprising a bridge member on one of the parts and a latch device having a flange on the other of said parts, said bridge member being movable in a direction at right angles to said hinge and having a lip engageable with said latch device flange to maintain the prong-holding parts partially open, an elevator block movable in a direction longitudinally of said hinge and having a cam surface arranged upon said movement to move beneath said lip and lift the bridge member away from said latch flange to permit further opening movements of the parts, springs normally urging said bridge member and elevator block in directions respectively to permit the said lip and flange to engage, and manually operating means for actuating the elevator block against the force to said springs.

ALFRED M. MARTIN.
